C. H. HOPMANN.
FORM FOR CONCRETE COLUMNS.
APPLICATION FILED JAN. 16, 1922.

1,430,376.

Fig. 1.

Patented Sept. 26, 1922.

Fig. 3.

The drawing shows a cylindrical container with a ribbed or fluted exterior. A horizontal band with several rectangular cutouts runs around the middle. Various parts are labeled with numbers: 23 at the top, 20 on the top band, 16, 15, 20, 25, 14, 15, 22, 24, 13, and 7. A small vertical pipe or tube is attached to the side. To the right, the text "Fig. 4." is written above a number 3, with a line pointing to the right side of the cylinder. The entire drawing is enclosed in a rectangular border.

Fig. 2

Fig. 6

Detailed description: The image contains two hand-drawn technical diagrams of a circular frame. The outer boundary is a thick line labeled '18'. Inside this, there is a thinner line labeled '21'. Along the inner boundary, there are several points where the inner line turns at a 90-degree angle, each labeled '23'. In the center of the circle, there is a small rectangular area labeled '7'. On the left side, there is a vertical line labeled '8' that extends from the inner boundary to the center. To the left of this line, there is a small rectangular area labeled '14'. A horizontal line labeled '10' extends from the inner boundary to the right, passing through the center. To the left of this line, there is a small rectangular area labeled '11'. A horizontal line labeled '12' extends from the inner boundary to the right, passing through the center. To the left of this line, there is a small rectangular area labeled '13'. A horizontal line labeled '17' extends from the inner boundary to the right, passing through the center. To the left of this line, there is a small rectangular area labeled '19'. A horizontal line labeled '22' extends from the inner boundary to the right, passing through the center. To the left of this line, there is a small rectangular area labeled '21'. The labels are handwritten in a cursive style.

A diagram showing a curved, segmented structure. Points 17 and 16 are located on the upper right and upper left respectively. Point 18 is located on the lower right, and point 15 is located on the lower left. The structure is divided into four quadrants by vertical and horizontal lines.

UNITED STATES PATENT OFFICE.

CHARLES H. HOPMANN, OF ST. LOUIS, MISSOURI.

FORM FOR CONCRETE COLUMNS.

Application filed January 16, 1922. Serial No. 529,593.

To all whom it may concern:

Be it known that I, CHARLES H. HOPMANN, a citizen of the United States, and resident of the city of St. Louis and State of Missouri, have invented certain new and useful Improvements in Forms for Concrete Columns, of which the following is a specification containing a full, clear, and exact description, reference being had to the accompanying drawings, forming a part hereof.

My invention relates to certain new and useful improvements in forms for concrete columns and the like, and has for its primary object the construction of a form which may be made in any number, size, and shape of sections, and provided with means for securely fastening the sections together.

In the drawings, Fig. 1 is a side elevation of my improvement with parts of the sections broken away.

Fig. 2 an enlarged section taken on the line 2—2 of Fig. 1, looking in the direction of the arrows.

Fig. 3 a fragmental sectional view, showing the manner of securing the stiffening bands to the sections.

Fig. 4 a fragmental sectional view, illustrating the manner of fastening the sections together.

Fig. 5 an inside view of one of the clips for holding the sections in assembled form; and

Fig. 6 a fragmental view of the stiffening bands, and how they may be tightened on the sections.

Referring to the drawings—

7 indicates one of the sections of my improved form which is made of any size, shape or suitable material. In the form shown the sections are cylindrical and have free ends 8 and 9, and when secured in assembled form, the edge 9 overlaps the edge 8, so as to make a tight seam. Secured to the end 8 by means of rivets 10 is a dove-tailed strip 11, and secured to the end 9 by means of rivets 12 is a dove-tailed strip 13. These dove-tailed strips are on the outside of the sections, and by means of clips 14, the sections are secured together along their free ends. The inside view of one of the clips for this purpose is illustrated in Fig. 5.

These clips are made out of metal and may be applied by inserting the same over the ends of the dove-tailed strips 11 and 13,

as illustrated in Fig. 2. They also may be removed from the dove-tailed strips for the purpose of opening up the sections and removing them from the work. Mounted on the ends of the sections 7 are stiffening bands 15 formed preferably as illustrated out of T-iron. These bands encircle the ends of the sections, and are formed in sections, and as illustrated, each band consists of two sections, such as 16 and 17. The band 16 is provided with holes 18 adjacent its ends and intermediate holes 19.

In Figs. 1 and 2 I have shown the band located on the upper section and also the band located on the upper end of the section 7. The band located on the upper end of the section 7 is formed of two pieces, such as 16 and 17, and is likewise provided with holes. The holes in the band located on the upper end of section 7, being slightly offset to the holes formed in the band located on the lower end of the upper section. This offset arrangement of the holes in the adjacent bands being illustrated in Fig. 6.

20 indicates pins which are inserted through the holes 18, and through the holes in the adjacent band. By driving these pins home the sections of the stiffening ribs are drawn tightly around the form sections. After the form sections have been secured together by means of the clips 14, and the stiffening bands 15 secured to the ends thereof, the next operation in assembling the form is to secure the different sections of the forms together.

In Fig. 4 I have illustrated the manner of securing the different form sections together. This locking arrangement comprises a yoke 21 secured adjacent the lever end of one of the form sections, and a yoke 22 secured adjacent to the top end of the adjacent form section. Located in the yoke 21 is a pin 23, and located in the yoke 22 is a tapered or wedge shaped pin 24.

25 indicates a locking pin or bar having formed in its upper portion an opening 26 to receive the pin 23, and in its lower portion an opening 27 to receive the wedge shaped key 24. By driving in the pin 24 its inclined face will exert a downward pull on the locking bar 25, and will consequently draw the ends of the adjacent form sections tightly together. The pins 20 as previously referred to, not only hold the stiffening bands to the form sections and tighten the same around the form sections, but al-

so prevent one form section shifting relative to the other section.

In Fig. 1 I have also illustrated the top form section, or what may be termed the cap section. This section is constructed like the other form sections, except that the dove-tailed strips 11 and 13 are cut away, as at 28 to permit the removal of the clips 14.

It will be observed from the foregoing 10 that my improved form may be made out of any number, size, or shape of form sections; that the free ends of each section, that is to say, where they are split for removal from the work, may be firmly 15 secured together and detached, and that I provide a detachable means for stiffening the adjacent ends of the sections, and to hold them in alinement; and further, that I have provided an improved locking device, simple and effective, for holding the 20 sections together and forming a tight joint.

Having fully described my invention, what I claim is:

1. A concrete form comprising a split 25 section, having its ends overlapping, dove-tailed strips secured along the overlapping

portions, clips for holding the sections in shape, sectional and detachable stiffening bands for the sections, means for tightening the bands on the sections and prevent 30 lateral shifting of one form section relative to the other, and a locking mechanism comprising a wedge for fastening the ends of the sections to each other.

2. A concrete form comprising a series of 35 split sections, a dove-tailed strip secured adjacent the free ends of said sections, clips adapted to embrace said dove-tailed strips for holding the sections together in assembled form, sectional stiffening bands located 40 on the adjacent ends of each section, means for tightening the sections of the bands around the sections, and to prevent one section shifting laterally relative to the other section, yokes secured to the form sections, 45 a locking bar mounted in the yokes, and means for shifting the locking bar in relation to said yokes for tightening the sections together.

In testimony whereof, I have signed my 50 name to this specification.

CHARLES H. HOPMANN.
